UNITED STATES PATENT OFFICE.

WILLIAM J. HIGGINS AND CHRISTOPHER J. SHERIDAN, OF BUFFALO, NEW YORK.

ELECTRIC SIGNALING SYSTEM FOR RAILWAYS.

No. 901,899.

Specification of Letters Patent.

Patented Oct. 20, 1908.

Application filed December 27, 1907. Serial No. 408,329.

To all whom it may concern:

Be it known that we, WILLIAM J. HIGGINS and CHRISTOPHER J. SHERIDAN, citizens of the United States, residing at Buffalo, in the county of Erie and State of New York, have invented certain new and useful Improvements in Electric Signaling Systems for Railways, of which the following is a specification.

10 Our invention relates to railway signaling systems and more particularly to those systems wherein a cautionary signal and a danger signal is given, not only by means of semaphore arms located at the side of the track but also by means of signal bells, lights, etc. within the cab of the engineer.

The object of our invention is to provide a mechanism whereby semaphore arms at the side of the track may be set either for danger or for a cautionary signal, whereby either cautionary or danger signals may be given within the cab to warn the engineer, and also whereby the steam valve may be operated to cut off the supply of steam to the engine and 25 the air brakes thrown on in case the danger signal is set and it is desired to bring the train to a full stop.

Our invention consists in the general arrangement of parts and detailed combinations of elements set forth in the appended description and specifically stated in the claims.

We have illustrated diagrammatically an embodiment of our system in the accompanying drawings, wherein

Figure 1 is a diagram of our system showing its application to four blocks of track. Fig. 2 is a diagrammatic front view of the cab signal.

40 Like reference characters throughout the several views refer to like parts.

Broadly speaking, we use an alternating current of say five hundred volts to induce the signal to be given automatically and directly into the cab of a locomotive or any other part of the train, when any other train or wreck is occupying another or the same block. One half of the transformer, the primary, is placed adjacent to the track 45 preferably outside of the rail. The other half of the transformer, the secondary, is carried on the train. The two coils are so arranged that they are in close proximity to each other at the passing point. When the 50 alternating current is thrown into the track coil, an induced current is set up in the

secondary coil of a train passing the primary coil. This actuates a polarized relay in the cab, and this through other circuits to be later described rings a signal bell or blows 60 whistles, actuates a light or color signal, cuts off the steam and sets the air brakes if desired.

There are two series of primary transformers or track coils used, one being set 65 on one side of the track and the other on the other, one series being used for the giving of cautionary signals, the other for the giving of danger signals. There are also on each train a secondary transformer which 70 moves adjacent to the cautionary signal track coil which is placed upon the side of the train adjacent to the series of cautionary signal track coils, and a secondary danger coil which is placed on that side of the car 75 adjacent to the series of primary danger coils.

In detail, A designates two rails of a track divided into four blocks or sections by proper insulation a. The two rails of each 80 block are respectively connected with a battery B, the rails of each block being part of a metallic circuit including the relays R', R², R³, R⁴, these relays being of any ordinary construction. The terminals of each relay 85 are connected as seen in Fig. 1, with the opposite rails of each block of track. Normally, the two rails of the track, the battery and the relay, are in a closed circuit acting to hold the switch arm S over to the back 90 stop X against the force of a spring 2.

The switch arm of each relay is connected by a conductor 3 to a primary cautionary signal coil C located at the side of the track two blocks ahead,—this coil being used for 95 the purpose of inducing a current in a secondary coil carried by the train. This coil is grounded as at c. After connecting with the coil C, the conductor, now numbered 3', leads to a motor M and from thence to the 100 "ground" 3". This motor raises the cautionary semaphore C' when the switch arm S is retracted by the spring 2 and bears against the back stop X', as shown at R². This back stop is connected as shown to a 105 main line F carrying an alternating current of say five hundred volts. The switch arm S is also connected by a conductor 5 to a primary coil D of the same character as the coil C and located at the side of the track 110 but on the opposite track from coil C. The conductor 5 is also connected to a motor M'

adapted to operate a semaphore arm D' indicating danger. The wire is then grounded as at 5'. On both the caution and danger semaphore towers, there are located the caution and danger lanterns L , L' , respectively red and green according to the usual practice. These lanterns are normally lighted by an electric lamp and these lamps are respectively connected in multiple with the conductor 3' and the conductor 5'. While the wire 3 from each relay runs to the cautionary coil and signal second preceding block of track, the danger coil D is located preferably just before the entrance to the block to which the relay belongs. When the block is entered upon by a train the battery B of the block is short circuited, the switch arm therefore is retracted and the alternating current from the main line F passes into the conductors 3 and 5, and passes to the cautionary coil C and to the danger coil D . These coils are of a construction well known in the art and need no special description. They are capable, as before explained, of inducing an electric current in the secondary coil passing adjacent to them.

It will be seen from the above description and from the drawing that we have provided a system wherein when a train arrives upon a block the alternating current from the main line is transmitted to a danger semaphore motor on the block preceding the one where the train is, and to an inducing primary coil adjacent thereto, while current is also transmitted to the second block preceding where it renders active the primary of an inducing coil and also operates a semaphore indicating caution. An induced current is set up from this cautionary and danger coil on any train passing them and this current so induced operates signal mechanism within the cab which will now be described.

Fig. 2 shows a diagrammatic view of the cab signal, also showing diagrammatically the means whereby the steam is cut off or the air brakes set upon the actuation of the signals in passing over a cautionary or danger transformer C , and D before described.

In essence, the construction comprises a cabinet or other suitable base upon which or within which the various parts of the apparatus may be inclosed. We have shown the construction as comprising a cabinet having a lower enlarged portion forming a compartment in which the relays are supported and an upwardly-projecting back piece upon which the two signal lamps are supported. These signal lamps are lettered C^2 D^2 to correspond with the cautionary transformer C and the semaphore arm C' , and the danger transformer and semaphore arm D , D' .

The front of the signal lamps is under normal circumstances covered by a shutter c hinged in any suitable manner and adapted

to drop open upon the actuation of the apparatus. Normally the solid fronts or covers c are closed on these lamps so that no light escapes from them. The glass of the lamp is suitably colored red or green to correspond with the ordinary signals of the railroad. Located above the shutter c of the lamp is a latch 6 which normally engages with the cover of the lamp and is provided or formed in one part with an armature 6' of a pair of electromagnets 7. These electromagnets are connected in circuit by conductors 7' with the pivoted arm 8''' of a highly polarized relay 8 which is normally held against the back stop 8'. This relay is connected in circuit with its respective transformer or secondary coil 9 near the track. The upper end of the vibrating arm 8''' engages against the back and front stops 8' 8''. Normally, as before stated, the pivoted arm 8''' engages against the back stop 8', being held thereto by the spring 8''', but when the secondary transformer coil 9 passes over the cautionary transformer or primary coil C' current passes into the relay 8, the arm is drawn over to the front stop 8'' and the circuit is completed through the conductors 7', 7, to the electromagnets 7. These are energized and withdraw the latch 6, releasing the shutter c and allowing it to fall, thus displaying the green signal light.

In order that an audible signal shall be given as well as the visual signal, the under side of the shutter may be provided with the contact plug 10 which is adapted to engage 100 between the two resilient wings 11 forming part of a circuit 12'' in which is located an electric bell 13. It will be seen therefore that when the shutter c drops the circuit 12'' is completed and the bell is sounded. In order 105 at the same time to cut off the steam supply to the engine we have provided a like arrangement; that is, the shutter c is provided with the contact plug 10' which engages between the resilient wings 11', thus closing the local 110 circuit 14 in which is an electromagnet 15. 16 designates the steam pipe provided with a valve 17, this valve being connected to a lever 18. This lever is normally engaged by a latch 19 and held in such position that the 115 steam valve is open. Upon the energizing of the electromagnets 15, however, the attraction exerted upon the armature 19' withdraws the latch 19 from engagement with the lever 18, thus allowing the lever to be 120 drawn over by a spring 20'' and to shut off the steam.

It will be seen that the segment 21 on which the lever works is provided with inclined ratchet teeth which are engaged by a hand-operated pawl 21'. These prevent the steam valve being opened too far and allow it to be set by hand but permit the lever to be drawn inward by the spring 20 immediately upon the actuation of the latch 19. 130

By these devices it will be seen, immediately upon the locomotive passing a cautionary track coil C the relay arm 8''' is thrown over to the back stop 8''. In order to hold it in this position until released by the engineer, we provide a latch 22; this latch is pivoted as at 22'. When the arm 8''' is thrown over the detent on the under side of the latch will drop over the end of the arm 8''' and thus hold the arm 8''' over against the back stop 8'' until released. One end of the latch 22 is provided with a rod 23 which projects upward through the case. When it is desired to return the parts to their original position as after passing a cautionary signal, the engineer depresses the rod 23 which raises the latch 22 whereupon the spring 8 draws the pivoted relay arm 8''' back to its original position breaking the lamp latch. The bell and throttle lever circuits are energized by the return of the lamp shutters. The engineer returns the lamp shutter c to its original position where it is engaged by the latch 6 and at the same time returns the throttle lever 18 to its original position where it is engaged by the latch 19. Exactly the same arrangement is made with regard to the danger signal portion of the apparatus. There the lamp D² is protected by the shutter d, this shutter being of the construction as before described, hinged at its bottom and adapted to drop down upon the withdrawal of a latch 24, this latch being actuated by the energizing of electromagnets 25 which through the conductors 26 are in circuit with the relay 27, the relay arm 27' being held normally against the back stop 28 by the spring 29. This relay is connected to a secondary coil 30 mounted upon the car truck on the side opposite to the secondary coil 9 of the caution signal. When this secondary coil passes over the primary danger coil D on the track, current is induced and the relay arm 27' is drawn over until it contacts with the stop 28' when the circuit is closed through the local circuit 26 energizing the magnets 25, raising the latch 24 and allowing the lamp shutter d to fall, displaying a red light as a warning to the engineer. The shutter d is also provided with the contact plugs 31 and 31'. The plug 31 closes the gap between the resilient wings 32 thus closing the local circuit 33 in which is the electromagnet 34. This acts upon the armature 35 carrying a latch 35' which latch normally engages with a lever 36 which is connected with a valve 37 for putting on the air brakes. Upon the initial movement of the arm 27 towards the back stop 28 it is caught by the latch 36 and held until released by the depression of the rod 36' in exactly the same manner as is the latch 22 before described. It will thus be seen that upon the secondary danger transformer coil passing over a primary danger transformer coil, the

visual signal will be given by the dropping of the shutter d, the bell 13 sounded and the air immediately put on. Taken in conjunction with the track wiring described before, it will be seen that the engineer upon his arrival on the second preceding block to the one upon which a train is located will receive the three signals: First, the cautionary semaphore arm at the side of the track will be raised; second, the cautionary light will show in the cab; and third, the bell will ring calling attention to the fact that the signals have operated; in addition to this the steam will be cut off automatically. The engineer can open the lever 18 immediately if he so desires or he may see the cautionary track signal set and not need to have the signals in the cab operate. He can prevent such operation and the cutting off of the steam by preventing the entire fall of the lamp shutter c and can reset the shutter in its original position by depressing the rod 23, thus breaking the circuit to the magnet 7 and thus allowing the latch 6 to fall in such position as to engage with the shutter c. 90

Upon the passage of a train over a danger transformer coil the visual and bell signal is again given to the engineer and at the same time the brakes are set. He can, however, again prevent the setting of the brakes or the actuation of the bell signal by preventing the full drop of the shutter d, and after passing the cautionary signal he depresses the rod 36', throwing up the latch 36 and allowing the spring 29 to draw the arm 27' over to its original position, thus breaking the local circuit 26 and allowing the armature 24 to fall in such position as would again engage the shutter d.

In detail, the operation of our system may be illustrated by imagining a train to be at the point Z on block No. 3, all trains moving in the direction of the arrow. In that case the release switch of that block would be moved to open the cautionary and danger circuit to the alternating current from the main line F. A cautionary signal would be given on block 1, the caution semaphore at that block being raised and the signal lamp illuminated. At the same time the primary coil C connected in the caution signal circuit would be energized and the cautionary coil upon a train coming upon block 1 and moving adjacent to the caution coil C' would receive a signal which by means of our mechanism would be transmitted to the engineer both audibly and visually and would, unless manually prevented, shut off the steam from the engine. At the same time the danger semaphore arm is raised at the end of block 2 and the primary coil in the danger circuit is energized. Thus a train reaching the end of block 2 and about to enter upon block 3 would receive a danger signal through the secondary connected to the danger signal ap- 130

paratus in the car and thereby the engineer would receive not only the visual signal from the signal arm but the visual signal from the dropping of the danger signal lamp shutter, the audible signal caused by the ringing of the bell, and also the air would be put on unless manually prevented.

It will be seen that our system is not dependent upon the setting of any signals by tower men or others. The semaphore arms at the side of the track are set automatically and even should they not work for some reason the engineer is yet warned by the signals within the cab.

15 It will be seen that with the three sets of signals given there is hardly any chance of the engineer not observing the passage of his train past a cautionary or danger coil and that even should he fail to observe the 20 signals, yet the steam will be cut off or the brakes put on automatically and without any action on his part. It will be seen that the system we have devised is simple as to wiring, while at the same time every precaution 25 is taken against the chance of accidents.

While we have referred to our signal apparatus as being applied to the cab of an engine, it is obvious that a signal cabinet as before described might be also placed in such 30 position at one of the other cars so as to be convenient to the conductor of the train so that the conductor himself can see where the engineer is running past signals and also note the presence or absence of trains on blocks 35 ahead.

Our construction may be adapted as will be readily seen to warning trains as to open switches and as to trains crossing the main track at cross-overs. This may be done by 40 placing a relay circuit closer on the switch and putting the caution and danger coil a suitable distance down the track and located a short distance from each other. Thus when the switch is open the relay is closed 45 and the caution and signal coils actuated. The crossing track will be wired in the same manner as any one of the blocks of track referred to in the description of Fig. 1 and the wires carried to the necessary caution 50 and danger coils on the main track. Thus when a train is on the cross-over the caution and danger coils are actuated and the proper signal is given which will stop the train on the main line or vice versa. In 55 view of these uses of our construction we do not wish to be limited entirely to what are known as block signal systems.

Having described our invention what we claim is:

60 1. In a railway signal system, separate blocks of track insulated from each other and each block connected in circuit with a battery, a relay magnet in circuit with each block and energized by said battery, a main line leading from a source of current, a relay

switch for each block normally held from electrical connection with said main line by said relay magnet when energized, means whereby the switch may be actuated to electrically connect with said main line when 70 the relay magnet is deenergized, and a cautionary circuit electrically connected to said switch extending from said relay to a preceding block of track, and there provided with a primary coil and connected to the 75 motor of a caution signal semaphore arm, a danger signal circuit electrically connected with said relay switch and extending to a preceding block having therein primary coils of a transformer, and a motor for actuating the danger signal semaphore arm, in combination with secondary coils mounted upon a car in such position as to be moved adjacent to the cautionary and danger track coils, said secondary coils being connected 85 to signal mechanism within the car indicating the passing of the car adjacent to said primary coils.

2. In a railway signal system, separate blocks of track insulated from each other 90 and each block connected in circuit with a battery, a relay magnet in circuit with each block and adapted to be short-circuited by the arrival of a train upon that block, a main line leading from a source of alternating current, a switch for each block, a connection from said main line to a terminal with which the switch is adapted to contact in one position, said switch being normally held from electrical contact with said terminal by said relay magnet when energized, 100 and connections from said switch to circuits having in each a primary coil of a transformer, in combination with secondary coils mounted upon a train in such position 105 as to pass adjacent to said primary coils, and means whereby the current so induced in the secondary coils will operate a signal.

3. In a railway signal system, separate blocks of track insulated from each other 110 and each block connected in circuit with a battery, a relay magnet in circuit with each block and adapted to be short-circuited by the arrival of a train upon that block, a main line leading from a source of alternating current, a switch for each block, a connection from said main line to a terminal with which the switch is adapted to contact in one position, said switch being normally held from electrical contact with said terminal by said relay magnet when energized, 115 connections from said switch to circuits having in each a signal motor and semaphore signals adapted to be operated by said motor, and primary transformer coils in said circuits, in combination with secondary coils mounted upon the train in such position as to pass adjacent to said primary coils, and means whereby the current so induced in the 120 secondary coils will operate the signal.

125 130

4. In a railway signal system, separate blocks of track insulated from each other and each block connected in circuit with a battery, a relay magnet in circuit with each block and adapted to be short-circuited by the arrival of a train upon that block, a main line leading from a source of alternating current, a switch for each block, a connection from said main line to a terminal with which the switch is adapted to contact in one position, said switch being normally held from electrical contact with said terminal by said relay magnet when energized, connections from said switch to circuits having in each a signal motor and semaphore signals adapted to be operated by said motor, and primary transformer coils in said circuits, in combination with secondary coils mounted upon the train in such position as to pass adjacent to said primary coils, a polarized relay connected to each of said secondary coils, a local circuit normally open but closed upon the energizing of the said relay, said local circuit having therein a battery and an electromagnet, a signal lamp and a shutter connected to said signal lamp normally closing the same, and an armature on said electromagnet adapted to release said shutter and allow the same to fall.
5. In a railway signal system, separate blocks of track insulated from each other and each block connected in circuit with a battery, a relay magnet in circuit with each block and adapted to be short-circuited by the arrival of a train upon that block, a main line leading from a source of alternating current, a switch for each block, a connection from said main line to a terminal with which the switch is adapted to contact in one position, said switch being normally held from electrical contact with said terminal by said relay magnet when energized, connections from said switch to circuits having in each a signal motor and semaphore signals adapted to be operated by said motor, and primary transformer coils in said circuits, in combination with secondary coils mounted upon the train in such position as to pass adjacent to said primary coils, a polarized relay connected to each of said secondary coils, a local circuit normally open but closed upon the energizing of the said relay, said local circuit having therein a battery and an electromagnet, a signal lamp and a shutter connected to said signal lamp normally closing the same, an armature on said electromagnet adapted to release said shutter and allow the same to fall, a throttle valve closing the steam supply pipe of the engine, a latch holding said valve open, means for closing said valve when the latch is raised, an electromagnet having an armature connected to the latch to raise the same, a local circuit in which said electromagnet is connected, said circuit being normally broken, a plug attached to the lamp shutter adapted to close said local circuit and thereby release the said throttle valve, a bell circuit normally open having therein an electric bell and battery, and a plug on the lamp shutter adapted to close said bell circuit when the shutter falls.
6. In a railway signal system, separate blocks of track insulated from each other and each block connected in circuit with a battery, a relay magnet in circuit with each block and adapted to be short-circuited by the arrival of a train upon that block, a main line leading from a source of alternating current, a switch for each block, a connection from said main line to a terminal with which the switch is adapted to contact in one position, said switch being normally held from electrical contact with said terminal by said relay magnet when energized, connections from said switch to circuits having in each a signal motor and semaphore signals adapted to be operated by said motor, and primary transformer coils in said circuits, in combination with secondary coils mounted upon the train in such position as to pass adjacent to said primary coils, a polarized relay connected to each of said secondary coils, a local circuit normally open but closed upon the energizing of the said relay, said local circuit having therein a battery and an electromagnet, a signal lamp and a shutter connected to said signal lamp normally closing the same, an armature on said electromagnet adapted to release said shutter and allow the same to fall, a throttle valve closing the steam supply pipe of the engine, a latch holding said valve open, means for closing said valve when the latch is raised, an electromagnet having an armature connected to the latch to raise the same, a local circuit in which said electromagnet is connected, said circuit being normally broken, a plug attached to the lamp shutter adapted to close said local circuit and thereby release the said throttle valve, a bell circuit normally open having therein an electric bell and battery, and a plug on the lamp shutter adapted to close said bell circuit when the shutter falls.
7. In a railway signal system, separate blocks of track insulated from each other and each block connected in circuit with a battery, a relay magnet in circuit with each block and adapted to be short-circuited by the arrival of a train upon that block, a main line leading from a source of alternating current, a switch for each block, a connection from said main line to a terminal with which the switch is adapted to contact in one position, said switch being normally held from electrical contact with said terminal by said relay magnet when energized, connections from said switch to circuits having in each a signal motor and semaphore signals adapted to be operated by said motor, and primary transformer coils in said circuits, in combination with secondary coils mounted upon the train in such position as to pass adjacent to said primary coils, a polarized relay connected to each of said secondary coils, a local circuit normally open but closed upon the energizing of the said relay, said local circuit having therein a battery and an electromagnet, a signal lamp and a shutter connected to said signal lamp normally closing the same, an armature on said electromagnet adapted to release said shutter and allow the same to fall, a throttle valve closing the steam supply pipe of the engine, a latch holding said valve open, means for closing said valve when the latch is raised, an electromagnet having an armature connected to the latch to raise the same, a local circuit in which said electromagnet is connected, said circuit being normally broken, a plug attached to the lamp shutter adapted to close said local circuit and thereby release the said throttle valve, a bell circuit normally open having therein an electric bell and battery, and a plug on the lamp shutter adapted to close said bell circuit when the shutter falls.

to pass adjacent to said primary coils, a polarized relay connected to each of said secondary coils, a pivoted latch for engaging the arm of said polarized relay when the relay has been energized and the arm moved to close the local circuit, means whereby said latch may be manually lifted, means for drawing the arm back to its normal position, a local circuit connected at one end to 10 said arm and at the other with a terminal with which the arm contacts when the relay is energized, said circuit including a battery and an electromagnet, a signal lamp and a shutter connected to said signal lamp normally closing the same, an armature on said electromagnet adapted to release said shutter and allow the same to fall, a throttle valve closing the steam supply pipe of the engine, a latch holding said valve open, means for closing 15 said valve when the latch is raised, an electromagnet having an armature connected to the latch to raise the same, a local circuit in which said electromagnet is connected, said circuit being normally broken, and a plug attached to the lamp shutter adapted to close the said local circuit and thereby release the said throttle 20 valve.

8. In a railway signal system, separate 30 blocks of track insulated from each other and each block connected in circuit with a battery, a relay magnet in circuit with each block and adapted to be short-circuited by the arrival of a train upon that block, a 35 main line leading from a source of alternating current, a switch for each block, a connection from said main line to a terminal with which the switch is adapted to contact in one position, said switch being normally 40 held from electrical contact with said terminal by said relay magnet when energized, connections from said switch to circuits having in each a signal motor and semaphore signals adapted to be operated by said motor, 45 and primary transformer coils in said circuits, in combination with secondary coils

mounted upon the train in such position as to pass adjacent to said primary coils, a polarized relay connected to one of said secondary coils, a local circuit normally open 50 but closed upon the energizing of the said relay, said local circuit having therein a battery and an electromagnet, a cautionary signal lamp, and a shutter connected to said cautionary signal lamp normally closing the 55 same, an armature on said electromagnet adapted to release said shutter and allow the same to fall, a throttle valve closing the steam supply pipe of the engine, a latch holding said valve open, means for closing 60 said valve when the latch is raised, an electromagnet having an armature connected to the latch to raise the same, a local circuit in which said electromagnet is connected, said circuit being normally broken, a plug attached to the lamp shutter adapted to close the said local circuit and thereby release the said throttle valve, a local circuit connected to the other of said polarized relays normally open but adapted to be closed by the 70 energizing of said polarized relay, a battery and electromagnets in said circuit, a danger signal lamp, a shutter normally closing the same, a latch for holding said shutter closed 75 attached to the armature of said electromagnets, said latch being adapted to be raised to release the shutter when the electromagnets are actuated, an air brake valve, a latch for holding said valve open and connected to the armature of said electromagnets, and 80 means for closing the said air brake valve when the latch is released.

In testimony whereof, we have signed our names to this specification in the presence of two subscribing witnesses. this 11th day of 85 December 1907.
